A. FLOHR,
SAW GUARD.
APPLICATION FILED AUG. 2, 1912.

Patented Apr. 28, 1914.

UNITED STATES PATENT OFFICE.

ANDREW FLOHR, OF COLORADO SPRINGS, COLORADO.

SAW-GUARD.

1,094,710.

Specification of Letters Patent. Patented Apr. 28, 1914.

Application filed August 2, 1912. Serial No. 712,973.

To all whom it may concern:

Be it known that I, ANDREW FLOHR, a citizen of the United States, residing at Colorado Springs, county of El Paso, and State of Colorado, have invented certain new and useful Improvements in Saw-Guards; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in guards for saws, of the circular, or buzz, type. Heretofore, so far as I am aware, the portion of a saw of this character which extends above the table or bench is so exposed as to make it exceedingly dangerous for workmen and others in the immediate vicinity of the saw.

My object is to provide a safety device, or guard, which shall cover the saw in such a manner that when not in use there can be no possible danger of accident, the said guard also serving to protect the workman while using the saw. To this end I mount upon the bench containing the slot through which the segment of the saw protrudes, a stationary frame, one bar of which is in vertical alinement with the saw blade, and occupies a position above the same, while the other bar, though connected with the first-named bar and forming a support therefor, is outwardly and laterally inclined, its outer extremity being connected with an upright member applied to the bench. A pair of dogs, or pointed members, is supported upon this frame and adapted to engage the piece of timber during the sawing operation, the said dogs being arranged to allow the board to travel forwardly to keep pace with the cutting action of the saw, but adapted to prevent its return movement, thus making it impossible for the saw to drive the board in the rearward direction, as sometimes happens with serious results.

Pivotaly mounted upon the stationary frame is the guard proper, which occupies a position upon the opposite side of the saw from the aforesaid dogs, the plane of the saw being between the guard and the dogs. This guard is constructed to move

upwardly as the board, or plank to be sawed, is moved into position, the forward end of the guard being upwardly and rearwardly inclined for the purpose. The guard rests upon the board, or piece of timber, during the sawing operation, and as soon as the work is completed and the board is out of the way, the guard drops into engagement with the top of the bench and acts as a shield for the purpose heretofore outlined.

In order that the weight of the guard may not interfere in any way with its operation, it is counterbalanced so that only slight upward pressure on its free end is necessary in order to cause it to rise in response to the forward pressure of the part to be sawed. This counterbalancing device consists of a flexible member, as a chain, rope, or cable, connected with the guard at one extremity, while its opposite extremity is connected with a weight, the chain engaging a supporting pulley intermediate its extremities.

In order to prevent the guard from being thrown out of position, either accidentally or by design, one of the bars of the stationary frame is bent at its rear extremity out of its normal plane and into the path of the lower edge of the rear of the guard, thus limiting the upward movement of the guard and preventing the latter from being turned on its pivot out of its guarding, or shielding, position.

Having briefly outlined my improved construction, I will proceed to describe the same in detail, reference being made to the accompanying drawing, in which is illustrated an embodiment thereof.

In this drawing: Figure 1 is a side elevation of my improved guard, shown in connection with a saw, the bench of the latter being shown in section on the line 1—1, Fig. 2. Fig. 2 is a top plan view of the same. Fig. 3 is a cross section taken on the line 3—3. Fig. 4 is a cross section taken on the line 4—4, Fig. 2, looking toward the left, or in the direction of the arrow.

The same reference characters indicate the same parts in all the views.

Let the numeral 5 designate a bench, or table, upon which the saw 6 is mounted, the top of the table having the usual slot 7 in the plane of the saw, and through which

the latter protrudes, a segment of the saw extending above the top of the bench to correspond with the required exposure for the thickness of the board or plank 8 to be sawed. It will be understood that the top 5 of the bench is vertically adjustable by any suitable means to regulate the area of the segment of the saw which shall be exposed above the top of the bench. As shown 10 in the drawing, this is accomplished by means of vertically arranged screws 10 threaded in nuts 12 mounted on the stationary part of the bench, the upper extremities of the screws engaging the top of the table 15 on its under surface. This structure is of ordinary character, and nothing is claimed thereon.

Mounted above the saw, and in the plane thereof, is a bar 13 which is supported at 20 its forward end by an upright piece 14 which also occupies a position in the plane of the saw, and at the forward extremity of the slot 7. This bar 13 is further supported by a bar 15 having a portion 16 arranged 25 parallel with the bar 13 and spaced therefrom, as shown at 17, two dogs 18 being connected with the bars, their upper extremities being located in the slot 7 and supported by means of pivot pins 19. These dogs 30 are arranged to swing freely in a plane at one side of the saw, but in close proximity thereto. From the forward extremity 20 of the part 16 of the bar 15, the latter has a part 21 which extends outwardly and for 35 wardly, its outer extremity being bent to occupy a position parallel with the edge of the top of the bench, as shown at 22, this part being secured by fastening devices 23 to the upper extremity of an upright post 40 24, the latter being secured to one edge of the top of the bench by means of fastening devices 25. The part 21 of the bar 15 extends across and above the space which is occupied by the portion of the board on the 45 right-hand side of the saw during the sawing operation, the term "right-hand side" being used with reference to the position of the operator standing at the rear of the bench and moving the board forwardly to 50 keep pace with the cut of the saw. The rear extremity of the bar 13 is bent inwardly toward the plane of the saw as shown at 26 in order to bring it into the path of a part 55 of the guard, as heretofore more fully explained.

The guard proper consists of a bar 27 pivotally connected at its forward extremity with the corresponding end of the stationary bar 13 by means of a bolt or other suitable fastening device 28, a spacing-sleeve 29 being interposed between the bars 13 and 27 in order to throw the pivoted bar well beyond the plane of the saw and leave a clear operating space for the latter. To 60 the rear extremity of the bar 27 is secured

a triangular member 30 which consists of two parts 31 and 32 connected at the bottom as shown at 33, the part 33 closing the space at the bottom of the member between the parts 31 and 32 and also connecting the latter, the said member consisting of an integral piece of material. The rear end 34 of the bar 27 passes between the two parts 31 and 32 of the member 30 and is bent slightly downwardly to correspond with the 70 shape of the upper part of the member 30, the bar being secured to the member 30 by fastening devices 35. The lower portion of this triangular member is upwardly inclined from the forward and lowermost 75 point 36 of the said member which normally rests upon the top of the bench. This upwardly inclined edge 37 extends to a point 38 of the triangular member, which is sufficiently raised from the top of the bench to 80 permit the introduction of one end of the board, or plank, 8, or other piece of timber to be acted on by the saw, and by virtue of the pivoted or inclined edge 37 of the member 30, the guard will be raised as the board 80 is thrust forwardly toward the saw, the guard in this event being supported by the board 8 and resting thereon during the sawing operation.

A plate 39 forming a part of the guard is 95 pivotally connected as shown at 40 with the bolt or pivot pin 28, and occupies a position at one side of the bar 27, the said plate being arranged to partly conceal the saw on the left-hand side of the user when the 100 saw is not in use. This plate 39, may be of any suitable size. As illustrated in the drawing, it is narrowest at its forward, or pivot, extremity, and increases in width as it extends rearwardly, its rear, extremity being approximately of the same width 105 as the forward extremity of the member 30. The forward extremity of this plate passes between the two parts 31 and 32 of the triangular member 30, and the lower rear corner of the plate normally rests upon the bottom or closed part 33 of the member 30 whereby the plate 39 normally moves with the bar 27 and the member 30 of the guard. This plate 39, however, is independently 110 movable, (see the dotted lines in Fig. 1,) for the purpose of exposing the saw on the left-hand side in order to measure the segment extending above the top of the table during the adjustment of such top to 115 correspond with the thickness of the board or other member to be acted on by the saw. The bar 27 is provided, on its upper edge, near its rear extremity, with a perforated lug 41 with which one extremity of a chain 120 42, or other flexible device, is connected, the said chain passing over a pulley 43 and having a counterbalance weight 44 connected with its opposite extremity. This weight is of such mass as to partly overcome the 125 130

5 weight of the guard, but it is also so regulated that the guard will resume its normal position in engagement with the top of the table as soon as the board, or other article to be sawed, is removed from the bench. The weight 44 is sectional, and may be regulated as desired.

10 The two dogs 18 extend downwardly nearly to the top of the table when the saw is not in use, and their lower extremities are made sharp to prevent the rearward movement of the board after it has once been brought into engagement with the saw. These dogs swing forwardly freely in response to the forward movement of the board, and occupy a forwardly inclined position with their sharp ends in contact with the board, but offering no resistance to its forward movement. However, these dogs 15 will prevent the rearward movement of the board, since their sharp extremities will indent the latter and lock it against accidental rearward travel.

15 From the foregoing description, the use and operation of my improved saw-guard will be readily understood. The top of the table, or bench, is equipped with an adjustable gage-plate 45, which occupies an edge-wise position upon the bench, and is 20 laterally adjustable by means of a slotted arm 46 and a set-bolt 47, in the usual manner. Assuming that this gage is adjusted to engage one edge of the board 8, the machine is ready for use. Assuming that the 25 rear extremity of the guard, at the point 36, is resting upon the top of the table, the forward end of the board is thrust against the beveled edge 37 of the member 30, and as the board is moved forwardly its action 30 on such edge imparts a corresponding lifting movement to the guard, which rises until it rests upon the upper surface of the board. As the board is moved forwardly into engagement with the saw, the latter performs 35 its function in the usual manner, the guard maintaining its position on top of the board and engaging the latter lightly in consequence of the action of the counter-balance weight 44, thus preventing the 40 guard from marring or marking the board to be sawed in case the upper surface of the latter is smooth or polished. It will be understood, however, that the part of the guard which rests upon the board at the 45 point 36 will be made perfectly smooth, and as this part is of appreciable width, (see the part 38 in Fig. 4,) there will be no tendency to mark or mar the board upon which the guard rests. After the board has been 50 moved over the bench and cut in two by the saw, the guard automatically will resume its normal position as soon as the part of the board which it engaged is out of the way. When it is desired to regulate the 55 top of the table to vary the protruding seg-

ment of the saw 6, the guard member 39 may be raised independently of the body of the guard, as heretofore explained.

It must be understood that my improved guard is equally applicable for the protection of saws for cutting metal as for the protection of wood-cutting saws.

Having thus described my invention, what I claim is:

1. In a saw-guard, the combination with 75 a bench and saw, of a support mounted on the bench and having a stationary bar extending above the saw and in the plane of the latter, and a guard pivotally connected with the support at one extremity and arranged beyond the plane of the saw but in close proximity thereto, the free extremity of the guard being open while the corresponding extremity of the stationary bar projects thereinto and forms a stop to limit 80 the movement of the guard upon its pivot.

2. In a saw-guard, the combination with 85 a bench and saw, of a support mounted on the bench in the plane of the saw and including a stationary bar extending above the saw and in the plane thereof, and a guard pivotally connected with the support at one extremity and arranged parallel with the stationary bar beyond the plane of the saw, but in close proximity thereto, the free 90 extremity of the guard being hollow to receive the corresponding extremity of the stationary member, the hollow portion of the guard being closed at its lower edge to engage the extremity of the stationary bar 95 which forms a stop to limit the upward movement of the guard farther than is necessary for operating purposes, substantially as described.

3. The combination with a bench and saw 100 of a stationary member extending upwardly from the bench in the plane of the saw and located forward of the same, the said member having a bar extending rearwardly above the saw and in the plane of the latter, 105 and a guard pivotally connected with the forward extremity of the bar and arranged parallel with the latter beyond the plane of the saw, in close proximity thereto, the said guard having a hollow part at its free extremity arranged to receive the corresponding extremity of the stationary bar which is arranged to limit the upward movement 110 of the guard by engaging the hollow extremity of the latter, the said extremity normally resting on the bench and having a beveled surface extending upwardly from the bench, the pivoted guard also including 115 a plate arranged to act in unison with the body portion of the guard, but movable independently of the latter, for the purpose set forth.

4. The combination with a bench and saw 120 of a stationary bar arranged above the saw and in the plane of the latter, a guard pivot- 125

ally connected at one extremity and occupying a plane on the opposite side of the stationary bar, the free extremity of the pivoted guard being recessed to receive the corresponding extremity of the stationary bar which serves to limit the upward movement of the guard farther than is necessary for operating purposes, the guard being also equipped with a plate normally moving in

unison with the body of the guard, but adapted to move independently thereof, substantially as described.

In testimony whereof I affix my signature in presence of two witnesses.
